BOTTLE

Laurie O. Graf, Wauwatosa, Wis., assignor to John Graf Company, Milwaukee, Wis., a corporation of Wisconsin

Application March 25, 1949, Serial No. 1,625

Term of patent 14 years

(Cl. D58—8)

To all whom it may concern:

Be it known that I, Laurie O. Graf, a citizen of the United States, residing at Wauwatosa, in the county of Milwaukee and State of Wisconsin, have invented a new, original, and ornamental Design for a Bottle, of which the following is a specification, reference being had to the accompanying drawing, forming part thereof.

I claim:

The ornamental design for a bottle, as shown and described.

LAURIE O. GRAF.
